OIL SUPPLY APPARATUS FOR OIL BURNERS

Ivan V. Abadjieff, Auburn, Mass., assignor to
 Leland-Gifford Company, Worcester, Mass., a
 corporation of Massachusetts

Application December 9, 1932, Serial No. 646,426

2 Claims. (Cl. 158—40)

This application is a continuation in part of my copending application Serial No. 631,984, filed September 7, 1932.

This invention relates to range type oil burners and fuel supply systems therefor.

A range type oil burner usually comprises a base having an open top fuel channel surrounded by inner and outer upstanding perforated combustion tubes between which the combustion of the fuel takes place. Liquid fuel as oil is supplied to the fuel channel from a reservoir wherein oil is maintained at a constant level from a supply of oil contained in an inverted oil reservoir or bottle, the reservoir usually being carried by a standard and the standard and reservoir supporting the inverted bottle.

The burner is ordinarily adapted to be ignited by the introduction of a flaming mass between the combustion tubes and into contact with the oil in the channel or a wick disposed therein. Convenient means for igniting the burner comprises an igniter of the type disclosed in my copending application Serial No. 628,708, filed August 13, 1932, wherein a long metal rod or shank has a handle at one end and an absorbent mass at the other end that is adapted to retain a charge of oil which when ignited can be inserted between the combustion tubes to ignite the oil in the oil channel of the burner.

It is an object of the present invention to provide a fuel supply device for range type oil burners especially constructed and arranged to support the igniting device above described with its absorbent mass immersed in the body of oil in the constant level reservoir so that the igniting device is constantly ready for use without having first to open the cover of the reservoir and dip the igniter therein as has been the practice heretofore.

The igniter of said application includes a snuffing device comprising essentially a flanged tube which is slidable on the shank of the device and can be dropped from the handle end downwardly into surrounding relation with the flaming absorbent mass after it has served its purpose, to extinguish the flame thereof.

A further object of the invention is the provision of a constant level oil supply device having a tube which extends upwardly above and communicates at its lower end with the constant level reservoir, the tube serving as a receptacle for the igniter when it is not in use, with the flange of the snuffing device constituting a cover for the upper end of the tube and serving to hold the igniter in position within the tube ready for instant withdrawal and with the absorbent mass at

the lower end thereof immersed in oil in the reservoir.

A further object of the invention is generally to improve the construction of oil supply apparatus for range burners.

Fig. 1 is a side elevation of an oil supply device embodying the present invention.

Fig. 2 is an enlarged sectional elevation of the device of Fig. 1.

Fig. 3 is a side elevation of a modified form of the invention.

The oil supply apparatus embodying the present invention includes a horizontally elongated constant-level oil reservoir 10 having a bottom and upstanding walls and open at the top and having its top closed by a removable cover 12 except at one end where an opening is provided into which the neck of an inverted oil bottle or reservoir 14 is inserted, the mouth of the neck resting upon ribs 16 of the reservoir which support the bottle vertically in inverted position. The mouth of the bottle is closed by the usual spring-loaded valve having a stem 18 that engages the bottom wall of the reservoir, when the bottle is on the ribs 16, and thus holds the valve open so that oil can flow from the bottle into the neck when the oil level in the reservoir sinks low enough to allow air to enter the mouth of the bottle and thereby permit oil in the bottle to flow into the reservoir and to raise the level of the oil sufficiently to seal the mouth of the bottle. Oil is conducted from the reservoir to the burner, not shown, by a pipe 20 that opens into the interior of the reservoir through an opening in a boss 22 that upstands above the bottom wall sufficiently to be above any accumulation of sediment thereon.

The reservoir and bottle are supported with the level of oil in the reservoir about at the normal level of the oil in the burner on the upper end of a pillar or tube 24 which is screw-threaded into a boss 26 that is integral with and depends below the bottom wall of the reservoir, the tube preferably being about in axial alignment with the bottle 14 so that the center of gravity of the weight supported by the tube is substantially coincident with the axis thereof. The lower end of the tube is carried by a pedestal or base 28 having preferably a circularly disposed bearing on the floor. The tube is vertically adjustable in the pedestal and is secured in any position by a set screw 30.

The igniting device forming a part of the present invention and described in my said application Serial No. 628,708, comprises a stiff metal rod or shank 36 of suitable length to be ex-

tended downwardly between the combustion tubes of a burner and into contact with the oil in the fuel channel thereof and is reflexed at its upper end into a loop 38 that constitutes a handle and carries an absorbent or porous mass 40, preferably of asbestos, at its lower end. The shank 36 is provided with a snuffing device that includes a tube 42 which is slidable thereon and is adapted to fall into a position where it envelopes and closely confines the absorbent mass 40 and thereby extinguishes the flame thereof. The tube is provided at its upper end with an outstanding flange 44 that is adapted to be grasped by the fingers of the hand that holds the handle 38 to hold the snuffing device on the rod during the use of the igniter to ignite the burner but the snuffing device, when released, is arranged to slide down the rod into a position over the absorbent mass to extinguish the flame thereof.

20 In accordance with the present invention, means are provided to support and enclose the igniting device in an out of use position with the absorbent mass 40 thereof immersed in the oil in the reservoir 10 so that it is constantly maintained impregnated with oil and thus is ready for instant service and with the snuffing device disposed adjacent the handle 38 so that it can be grasped more or less automatically and held adjacent the handle when the igniter is taken up 25 for use. For this purpose the end wall of the reservoir, remote from the ribs 16, is provided integrally with a boss 46 that overlies the oil in the reservoir and preferably has its lower face disposed above the oil. The boss is provided with a vertical passage that extends entirely therethrough and is internally screw-threaded. A vertical tube or pipe 48 is disposed above said boss and has its lower open end screw-threaded into the passage in said boss. Thus the lower 30 end of said tube is above and is open to the interior of the reservoir and the oil therein. The tube 48 extends upwardly close inside the bottle 14 and carries at its upper end a bottle supporting device 50 which embraces the bottle and holds it in vertical position and is secured detachably, if may be, to the upper part of the tube. The tube 48 is open at its upper end. The igniting device is located within said tube 48 and the flange 44 of the snuffing device overlies and

35

40

45

constitutes a closure for the open upper end of said tube. The snuffing device thus engages the handle 38 and supports it in position within the tube. The length of the tube 48 is adapted to be such that the igniting device therein is positioned with the absorbent mass 40 in contact with the body of oil in the reservoir so that it is maintained constantly impregnated with oil and is ready for instant service.

In the modification of the invention illustrated in Fig. 3, the main difference in the construction is that the supporting standard on tube 24 is connected with the oil reservoir directly under and in axial alignment with the igniter-enclosing tube 48 and is, in appearance, a continuation thereof. The pedestal or base 28a in this instance is extended mainly under the center of gravity of the elevated parts for stability.

I claim:

1. An oil supply for range type oil burners comprising a constant level oil reservoir, a supporting standard therefor, an inverted bottle having its neck seated upon and opening into said reservoir, a tube carried by said reservoir and extended upwardly thereabove alongside said bottle and having its lower end open to the interior of said reservoir, a bottle supporting device carried by said tube and engaged with said bottle, and an igniting device located removably within said tube and having its lower end immersed in the oil in said reservoir.

2. An oil supply for range type oil burners comprising a constant level oil reservoir, a supporting standard therefor, an inverted bottle having its neck seated upon and opening into said reservoir, a tube carried by said reservoir and extended upwardly thereabove alongside said bottle and having its lower end open to the interior of said reservoir, a bottle supporting device carried by said tube and engaged with said bottle, and an igniting device located removably within said tube having its lower end immersed in the oil in said reservoir and having a handle at its upper end, a snuffing device slidable on said rod and having an outstanding flange which rests upon the upper end of said tube and is engaged by said handle and supports said igniting device in the aforesaid position.

IVAN V. ABADJIEFF.
